UNITED STATES PATENT OFFICE.

LEE S. CHADWICK, OF EAST CLEVELAND, AND ARNOLD R. WHITTAKER, OF CLEVELAND, OHIO, ASSIGNORS TO THE CLEVELAND METAL PRODUCTS COMPANY, OF CLEVELAND, OHIO, A CORPORATION OF OHIO.

WATER-HEATER.

1,358,286.

Specification of Letters Patent. Patented Nov. 9, 1920.

Application filed March 11, 1915. Serial No. 13,571.

To all whom it may concern:

Be it known that we, (1) LEE S. CHADWICK and (2) ARNOLD R. WHITTAKER, residing at East Cleveland (1) and Cleveland (2), in the county of Cuyahoga and State of Ohio, have invented a certain new and useful Improvement in Water-Heaters, of which the following is a full, clear, and exact description, reference being had to the accompanying drawings.

This invention relates to water heaters, and particularly to devices of this character wherein liquid fuel is used as the heat producing medium.

The invention has for its objects to provide a water heater that is extremely efficient, and that is economical of operation; that is comparatively simple yet very rigid and substantial of construction; that is designed with the end in view of preventing undue accumulation of soot, and constructed in a manner to facilitate cleaning; wherein the water circulating apparatus and the combustion device are each an entire or "self-contained" unit; and to provide a substantial and convenient means for separably connecting said units.

The above and further objects, which will become apparent as this description proceeds, are attained in a water heater constructed in accordance with the accompanying drawing wherein we have shown a very practical and desirable embodiment of our invention; and while we will proceed to describe the same in detail, we wish to be understood as not limiting ourselves to such details further than is required by the terms of the annexed claims, and is rendered necessary by the state of the prior art.

In the drawing, Figure 1 represents a front elevation of the water heater; Fig. 2 is a right hand side elevation thereof; and Fig. 3 is a horizontal section on the line 3—3 of Fig. 1, showing the combustion device in plan.

We will now proceed to describe our invention by the use of reference numerals. Rising from a standard type of floor plate 1 (see Fig. 3) is a post 2, to which is adjustably connected the hollow, vertically disposed boss 3 of a cross beam 4, by means of a set screw 5. An L-shaped bracket 6 is at-

tached to each end of the cross beam 4, by means of a screw 7.

Supported from the upper ends of the brackets 6 is the base shell or heat collector 10 of what has already been referred to, in a general way, as the water circulating apparatus. The top of the shell is circular in plan, while its lower end is substantially elliptical, as indicated by the dot-and-dash line in Fig. 3. Pads 11 extend from the rear side of the shell 10, and the upper end of one of the brackets 6 is attached to each pad, by screws 12.

Supported by the horizontal branches of the brackets 6, is a pan 70, which constitutes the base of the combustion device. The pan is prevented from any appreciable lateral movement upon the brackets, by the down turned portions of the plates 71 and 72, that are connected to the bottom of the pan and bear upon the respective brackets. The plate 71 has a portion 73 that extends in under the edge of the bracket whereon it rests, and prevents the adjacent end of the pan from being elevated. When it is desired to clean the burners, the combustion device may be slipped forwardly on the brackets from beneath the base shell 10 of the water circulating apparatus, or it may be removed entirely from the brackets by elevating the right hand end of the device enough to permit the down-turn portion of the plate 72 to be moved to the left across the adjacent bracket 6, so as to allow the plate 71 to be unhooked from the other bracket. However, there is nothing to prevent sliding the device forwardly and entirely off of the brackets if desired, although the foregoing is considered more convenient.

Extending upward from the right hand end of the pan 70, is an inverted U-shaped support 74, to the horizontal portion of which is attached a branched pipe member 75. This member constitutes a Y, the ends of the fork whereof are connected by a web 76, that is preferably formed integral with the remainder of the member. The enlarged ends of the fork are internally threaded. As will be observed from Figs. 1 and 2, the stem of the member 75 is inclined upwardly from where it joins the fork. The member 75 is attached to the support 74 by a bolt 78.

that passes through the web 76, and the adjacent horizontal portion of the support 74, and is provided therebeneath with a nut 79.

A pair of pipes 80 have their threaded 5 right hand ends screwed into the internally threaded ends of the member 75, and said pipes extend parallel to each other across the pan 70, the opposite ends of said pipe being supported by a bracket 81 which rises 10 from the left hand end of the pan. The pipes are secured to said bracket by a strap 82, which is attached to the bracket by bolts 83. The left hand ends of the pipes 80 are closed by caps 84.

15 Applied to the externally threaded end of the member 75, is a liquid fuel distributing receptacle 85 of a well known type, and a reservoir 86 is adapted to be inverted over the distributing receptacle and supply it 20 with fuel. As a brace to assist in supporting the reservoir and the distributing receptacle and as a shield to protect them from the heat radiated from the combustion device, we employ a metallic plate 87 which 25 has its lower end turned at right angles to its body portion to form a flange which rests upon the horizontal portion of the support 74, and is attached thereto by bolt 89. The lower edge of the plate is notched to accommodate 30 the member 75. Slightly above the plane of the top of the reservoir 86, the plate 87 is bent outward and downward to where it has connection at 90, to a plate 91 that extends from the side of the distributing 35 receptacle.

A liquid fuel burner 92 is supported by the front pipe 80, and is located at about the longitudinal center of said pipe. One side of the burner has connection to the pipe 40 through a hook 93, and an elbow 94, which extends from the opposite side of the burner, is secured to the pipe by means of a clamp 95. We do not claim this burner as a part of our invention, but refer to Patent 45 No. 848,828, issued April 2nd, 1907, to William R. Jeavons, for a detail description of the burner. We will explain, however, that communication is established between the interior of the burner, and the pipe 80, through the elbow 94. The burner is provided with the usual wick raiser 96, and a chimney or drum 97 fits down the top of the burner and extends upwardly therefrom, and its upper end reposes a slight distance 50 below the bottom of the base shell 10 of the water circulating apparatus.

A pair of burners 98 are supported by the back pipe 80, and are spaced laterally from the front burner 92. The fact that the 60 burner 92 and the burners 98 are supported upon separate pipes, allows the burners to be nested closely enough together to cause the upper ends of the drums 99 of the burners 98 to be within the scope of the lower 65 end of the shell 10, as indicated in Fig. 3.

It will be observed that the upper ends of the drums 97 and 99 are spaced below the bottom of the shell 10. This arrangement is of great importance, since it insures a perfect circulation or draft through the drums, 70 even though the casing 48 should become clogged from any cause, such as the accumulation of soot or dust upon the inside wall of the casing, and upon the circulating elements inclosed thereby. It is obvious that 75 if the upper ends of the drums extended up into the shell 10, and the draft through the casing 48 were checked by reason of the existence of the aforesaid condition, the circulation through the drums would be materially checked and cause a backing up of the heat within the drums, which would result in an overheating of the burners to a dangerous degree, as will be well understood by those familiar with devices of this character. Therefore, we consider the spacing 80 of the upper ends of the drums a distance below the bottom of the shell, a very essential part of our invention.

It will be explained briefly that the liquid fuel is distributed from the receptacle 85, through the member 75 and the pipe 80, to the burners 92 and 98, wherein a constant level of the liquid fuel is maintained by the elevation of the distributing receptacle 85. 95 The burners may be lighted through the doors 100 of the burner drums, and the wicks may be adjusted by means of the wick-raisers 96.

The products of combustion will rise from 100 the burner drums into the base shell 10 and be drawn upward through a tortuous course around the outer edges of the circular elements and in through the open centers of the annular elements until they find their 105 escape through the flue opening 59 and pipe 61.

Having thus described our invention, what we claim is:—

1. The combination with a hydrocarbon 110 heating device and a water container, of a pair of L-shaped brackets to the upper ends of which said container is connected, said brackets extending downward from the container and beneath the same, the horizontal 115 branches being arranged to support the heating device in operative relation to the water container, the heating device having portions which extend down along opposite sides of the brackets thereby to prevent undue lateral movement of the combustion device with respect to the brackets.

2. The combination with a hydrocarbon heating device and a water container, of a pair of L-shaped brackets to the upper ends 125 of which said container is connected, said brackets extending downward from the container and beneath the same, the horizontal branches being arranged to support the heating device in operative relation to the 130

water container, the heating device having portions which extend down along opposite sides of the brackets thereby to prevent undue lateral movement of the combustion device with respect to the brackets, the heating device having also a portion which extends beneath one of the brackets.

5 In testimony whereof, we hereunto affix

our signatures in the presence of two witnesses.

LEE S. CHADWICK.

ARNOLD R. WHITTAKER.
